UNITED STATES PATENT OFFICE.

WALDEMAR DYRSSEN, OF NEW YORK, N. Y.

OPEN-HEARTH FURNACE.

Application filed June 28, 1923. Serial No. 648,253.

To all whom it may concern:

Be it known that I, WALDEMAR DYRSSEN, a citizen of the United States, and resident of the city, county, and State of New York, 5 have invented certain new and useful Improvements in Open-Hearth Furnaces, of which the following is a specification.

This invention relates to open hearth furnace installations and particularly to that 10 type of plant including a boiler which is adapted to be heated by waste gases, and particularly to installations wherein part of the waste gases are taken directly from the melting chamber into a boiler and the remaining part of the gases are led through 15 regenerators or checker-chambers to give up their heat thereto so that the combustion air or producer gas which is subsequently fed thereto will be preheated.

20 My invention is adapted to be used with the usual type of reversible furnace in which the gases are alternately withdrawn from the ends of the furnace and the combustion air and fuel are alternately introduced from 25 the opposite ends of the furnace. In order to control the direction or flow of that part of the waste gas which is to go directly to the boiler, alternately from each end of the furnace, it has heretofore been necessary to 30 use valves in each of the flues leading from the opposite ends of the furnace to the waste heat boiler. Such valves must necessarily be placed in the flues through which the gases of excessively high temperature flow. If 35 these valves are not water-cooled to an extremely high degree they are destroyed in very short time and when they are water-cooled, the waste gases are cooled down and hence give up a large portion of heat which 40 cannot be recovered as energy in the boiler.

In the furnace embodying my invention I 45 avoid the use of any valves whatever in the flues leading from the furnace to the boiler. There is a flue connecting each end of the furnace with the waste heat boiler and I provide means whereby I can cause the waste gas to flow from either end of the furnace to the boiler without the use of any valves in the flues. In the furnace shown I control the 50 passage of waste gas to the boiler by introducing a jet of gas under pressure at such a point between the melting chamber and the boiler that a suction is created on the waste gases which are withdrawn from the melting 55 chamber in such manner that there will be no

passage of gas through the flue leading from the boiler to the end of the furnace where the fuel and combustion air enter.

In order to maintain this action under varying conditions, either during each period of reversal or during the progress of the heat, I provide means for automatically regulating the quantity or pressure of the gas supplied to the jets.

An embodiment of the invention is illustrated in the accompanying drawings in which Fig. 1 is a diagrammatic plan showing the furnace in horizontal section, the regenerators, the waste heat boiler, the connecting flues and associated equipment:

Fig. 2 is a longitudinal section through the furnace on the staggered line 2—2 of Fig. 1;

Fig. 3 is a transverse section through one end of the furnace on the line 3—3 of Fig. 2; and Fig. 4 is a similar section on the line 4—4 of Fig. 2.

Fig. 5 is a diagrammatical plan showing the same furnace illustrated in Fig. 1 and in addition showing the automatic means for regulating the supply of fluid to 60 certain jets and also the automatic means for controlling the volume of gas drawn through the waste heat boiler.

In the drawings the furnace 10 is formed with rear walls 12 and front walls 14 having suitable charging openings 16 therein which are closed by doors, not shown. The furnace is provided with the usual roof 18, hearth 20, tapping spout 22 and flues 24 and 24' at opposite ends of the furnace. The flues 24 and 24' communicate with slag pockets 26 and 26' and these in turn communicate with the regenerator chambers 28 and 28'. The lower part of the regenerator chambers 28 and 28' are connected by flues 30 and 30' with a stack 32. Valves or dampers 34 and 34' are provided in the last named flues for controlling the direction of flow of the waste gases and combustion air through the furnace. A stack damper 36 is common to both flues 30 and 30' and also the flue 38 which leads to the waste heat boiler 40. The flue 38 is provided with a control damper 39 whereby the volume of gas flowing through said flue 38 to the stack can be controlled.

A fan 42 is provided for withdrawing part of the waste gases from the flue 38 through pipe 44 and discharging such gas through either of the pipes 46 or 46' accord-

ing to the setting of the reversing valve 48. The pipes 46 an 46' lead to nozzles 50 and 50' which are located at opposite ends of the furnace above ports 52 and 52' communicating with flues 54 and 54' leading to the waste heat boiler 40. The nozzles 50 and 50' are adapted to alternately direct a jet of gas toward the ports 52 and 52' so as to alternately cause the gas to flow 10 through the respective flues 54 and 54' to the boiler 40, it being understood that the reversing valve 48 can be shifted to render either set of nozzles 50 or 50' effective.

A blower 56 is provided for supplying air 15 to the respective ends of the furnace through the regenerators 28 and 28' this blower being connected by branch pipes 58 and 58' with the flues 30 and 30' leading to the regenerators. A reversing valve 60 is provided 20 for controlling the direction of flow to either end of the furnace.

In operation assuming that the valve 34 is closed and the reversing valve 60 is in the full line position shown, air will be 25 forced by the blower through the branch 58 and the flue 30 to the regenerator 28 where it will be preheated. This heated air passes through the slag pocket 26 and the flues 24 at the left hand end of the furnace 30 and through the outlet 62 where it mixes 35 with fuel introduced through the burner 64. The flame developed passes over the bath giving up part of its heat to the bath or metal charge and the waste gases are 40 withdrawn from the opposite end of the furnace partly through the opening 62' and partly through the ports 52' leading to the flue 54' communicating with the boiler. That part of the gas which passes through 45 the opening 62' flows downward through the flues 24' to the slag pocket 26' and thence to the upper part of the regenerator 28' where it gives up the greater part of its heat to the checker-bricks and then passes 50 by the way of the flue 30' to the stack 32, the valve 36 being normally open at all times and the valve 34' being open when the combustion air and fuel are introduced at the left end of the furnace. The hot waste 55 gases that pass out through the ports 52' meet the waste gases which are introduced under pressure from the nozzles 50'. This mixture of waste gases flows through the flue 54' into the boiler 40 where the gases give up their heat to generate steam before they are discharged through the flue 38 to the stack 32.

The waste gases discharged through the nozzles 50' are of such velocity and volume 60 that the pressure created in the flue 54' is the same as the pressure that exists in the flue 54, the ports 52 and the melting chamber of the furnace, with consideration to the static pressure. Because of this substantially balanced condition of the pressures

there will be no flow of gases from the melting chamber through the ports 52 and flue 54 to the boiler 40 or vice-versa. The condition created by the introduction of waste gases through the nozzles 50' therefore acts 70 like a shut-off valve in the ports 52 which communicate with flue 54 leading to the boiler. At this time no waste gases are introduced through the nozzles 50. The total volume of waste gas that passes through the 75 boiler 40 is regulated or controlled by the valve 39 in the flue 38. The flow of gas through the regenerators and the boiler respectively can also be automatically controlled by the temperature in flues 30 and 30'. Such control can regulate the valves 34 and 34' or the valve 39 as hereinafter more fully described. It is desired at all times to supply a sufficient but not excessive amount of gases through the regenerators in 80 order to properly preheat the combustion air. The pressure or volume of waste gases drawn through the boiler flue 38 to the nozzles 50 and 50' is regulated by the speed 85 of the fan 42.

At the end of a given period when the furnace is to be reversed, the valve 34' is closed and the valve 34 opened and the reversing valve 60 shifted to the dotted line position. The combustion air will then flow 90 through the regenerator 28', fuel will now be introduced through the burner 64' at the opposite end of the furnace and the waste gases will flow out through the ports 52 and 62 leading respectively to the boiler 40 and 95 regenerator 28. The valve 48 will be shifted so as to supply waste gas through the pipe 46 to the nozzles 50, therefore causing the waste gases to flow to the boiler through the flue 54 and equalizing the pressure in the flue 54' with that of the melting chamber so that no waste gas will flow from the right hand end of the furnace to the boiler. The amount or pressure of the gases supplied to the nozzles 50 and 50' respectively can be automatically controlled as 100 illustrated in Fig. 5 by the pressure or the current of gases in the flues 54 and 54' so that during various periods of operation and under varying conditions the flow of gases from the furnace to the boiler automatically takes place as outlined above. The means for securing this automatic regulation for convenience of illustration and simplification 105 of description is shown separately in a dia-grammatic way in Fig. 5. The furnace can be operated without such automatic regulating device, the speed of the motor for fan 42 being controlled manually and the operation of the valve 39 also being manually controlled. However, it is preferred to automatically control these parts and suitable 110 automatic control apparatus will now be described with particular reference to Fig. 5. In this figure I show pipes 70 and 70' which 115

enter the flues 54 and 54' respectively as close as possible to the furnace. A pipe 71 is introduced at the junction of the flues 54 and 54' under the boiler 40. The pipes 70 and 70' are both connected to a pipe 72 by a three way valve 73. The pipes 71 and 72 are communicated with separate chambers on opposite sides of the diaphragm 74 of a pressure regulator 75. This regulator carries fixed contacts 76 and 77 which are connected by wires 76^a and 77^a with a motor 78. The motor 78 and the diaphragm 74 are connected to the opposite terminals of a source of electrical energy indicated for example as a battery at 79. The motor 78 through the gearing 78^a and 78^b drives a feed screw 78^c which actuates a nut 80 adapted to cut in or out resistance 81 which is connected in circuit with a motor 82 which drives the fan 42. The fan 42 it will be remembered is adapted to supply waste gases either to the nozzles 50 or 50' according to the setting of the valve 48.

With the valve 48 set in the position shown in Fig. 1, pressure is supplied to the nozzles 50' and waste gases from the furnace enter the boiler through the flue 54'. The valve 73 at this time is so set that the pressure in the pipe 70 is transmitted through pipe 72 to the regulator 75 and the communication between the regulator and the pipe 70' is cut off.

If there is any pressure difference between the pipes 70 and 71 the diaphragm 74 will be deflected and a circuit will be made either through the contact 76 or 77 which will result in starting the motor 78 in one direction or the other so that the speed of the fan 42 will either be increased or decreased due to cutting out or cutting in resistance 81. Thus the pressure or draft balance is restored between the pipes 70 and 71 and consequently between the flue 54 and the boiler 40 due to the automatic regulation of the speed of the fan 42. When no pressure difference exists in the flue 54 between the points where the pipes 70 and 71 enter, practically no flow of gas occurs in said flue 54, which is the desired object. At reversal periods the valve 73 is turned to open communication alternatively between the pipes 70 and 70' respectively with the pipe 72 at the same time the valve 48 and other reversing valves in the system are operated.

I have provided means for automatically controlling the amount of waste gases taken through the boiler. If the volume of waste gas passed through the boiler is too large a proportion of the total gases from the furnace, the waste gases passing from the checker-chambers of the regenerators will be comparatively cool and the air subsequently passed through such regenerators will not be properly preheated. On the other hand if the amount passed through the boiler is

too small the gases passed through the checker-chambers to the stack will be of an excessive temperature and will represent a loss of heat which should have been utilized in useful work. It is clear that the temperature of the gas in the stack is therefore a good indication of the distribution of waste gases through the boiler and regenerators. I utilize this condition for automatically controlling the operation of valve 39 so as to pass the proper proportion of waste gas through the boiler and regenerators respectively. I provide a pyrometer 90 which projects into the stack and which is connected by wires 90^a and 90^b with an indicating instrument 91 of known design having an indicating hand 93^a adapted to make contact with either of the terminals 92 or 93. The terminal 92 is connected by a wire 94^a with a magnet 94 and the terminal 93 is connected by a wire 95^a with a magnet 95. The magnets 94 and 95 are adapted to actuate armatures 94^b and 95^b which in turn close circuits across contacts indicated at 96 and 97. These contacts are connected by wires 96^a and 97^a with the motor 98. When the circuit is made cross the contacts 96 the motor will be turned in one direction and when the circuit is made cross the contacts 97 the motor will be turned in the reverse direction. The motor 98 is connected by worm gearing indicated at 98^a with a screw 98^b operatively connected with the valve 39 in such manner that the valve will be opened or closed according to the direction of rotation of the motor. From the above it will be understood if the temperature in a stack in the vicinity of the pyrometer 90 is too low the valve 39 is lowered, that is partly closed, thus throwing more gas through the regenerator and restoring the proper balance. Or if the temperature is too high, the valve will be lifted or opened wider so as to pass a greater proportion of the waste gases through the boiler. Instead of using the valve for this purpose it is to be understood that a motor driven fan could be substituted in which case the motor for such fan would be regulated in a manner similar to that in which the motor 82 is regulated.

The above described furnace is adapted to burn tar, oil, powdered coal, coke oven or natural gas and similar fuels. But the invention can also be used in connection with furnaces using producer gas as fuel either when it is preheated or when such producer gas is introduced directly into the chamber from the producer without preheating. Instead of supplying waste gas to the nozzles 50 and 50' I may supply air instead. The jets of gas or air in addition to serving the function above described, serve to cool down the extremely

41
 hot gases emanating from the melting chamber to such an extent that little or no melting off of the brickwork in the hot flues will occur and very little slag will be 5 formed in these flues. It is possible to insulate flues 54 and 54' so that practically no loss of heat will occur and consequently a greater amount of heat can be recovered for the generation of steam in the 10 boiler.

Though I have described with great particularity details of the embodiment of the invention herein shown, it is not to be construed that I am limited thereto as changes 15 in arrangement and substitution of equivalents may be made without departing from the invention as defined in the appended claims.

What I claim is:

20 1. In combination with an open hearth furnace, a boiler adapted to be heated by waste gas from the furnace, and means for alternately directing jets of gas to effect the discharge of the waste gas from the opposite ends of the furnace to the boiler.

25 2. In combination with an open hearth furnace, a boiler adapted to be heated by waste gas from the furnace, and means for directing jets of fluid for controlling the direction of flow of the waste gas from the furnace to the boiler whereby the use of valves in the passages leading from the furnace to the boiler is rendered unnecessary.

30 3. The combination with an open hearth furnace and a boiler adapted to be heated by waste gas from the furnace, of flues connecting the opposite ends of the furnace with the boiler, ports communicating with said flues and means for discharging jets of gas toward said ports to determine which of said flues the gas will flow through to reach the boiler.

35 4. The combination with an open hearth furnace and a boiler adapted to be heated by waste gas from the furnace, of flues connecting the opposite ends of the furnace with the boiler and means for alternately discharging jets of gas at points in juxtaposition to the ports in the furnace leading to said flues so as to alternately cause the waste gas to flow through the flues at opposite ends of the furnace without the use of valves between the boiler and the furnace.

50 5. In combination with an open hearth furnace and a boiler adapted to be heated by waste gas from the furnace, flues connecting the opposite ends of the furnace with the boiler, nozzles arranged to discharge jets into said flues and means for alternately supplying fluid pressure to each of said nozzles.

55 6. In combination with an open hearth furnace and a boiler adapted to be heated

by waste gas from the furnace, flues connecting the opposite ends of the furnace with the boiler, nozzles arranged to discharge jets into said flues, a blower, and means for alternately connecting the nozzles at the opposite ends of the furnace with said blower. 70

7. The combination of an open hearth furnace having regenerators connected with the opposite ends thereof, means for reversing the direction of travel of the combustion 75 air and waste gases through the furnace and regenerators, means for supplying fuel at the ends of the furnace, a boiler, flues connecting the opposite ends of the furnace with the boiler and means for alternately 80 discharging jets of gas in proximity to the points at which said flues enter the furnace so that part of the waste gas is alternately withdrawn from each end of the furnace and led to the boiler. 85

8. In combination, an open hearth furnace having means for introducing air and fuel at each end of the furnace, a boiler adapted to be heated by the waste gases from the open hearth furnace, flues connecting the ends of the furnace with said boiler and means for introducing a jet of gas or air under pressure at such a point between the melting chamber of the furnace and the boiler that a suction is created on the waste 90 gases which are withdrawn from the melting chamber so that there will be substantially no passage of gas through the flue leading from the boiler to the end of the furnace where the fuel and combustion air 95 enter. 100

9. In combination an open hearth furnace having regenerators connected therewith, a boiler adapted to be heated by part of the waste gases from the furnace, a motor, means responsive to temperature changes of the waste gases passed through said boiler and said regenerators for controlling the operation of said motor and a member actuated by said motor adapted to control the proportion of waste gas drawn through said boiler from said furnace. 105

10. In combination with an open furnace and a boiler adapted to be heated by waste gas from the furnace, flues connecting the 110 opposite ends of the furnace with the boiler, nozzles arranged to discharge jets into said flues, a blower, and means for alternately connecting the nozzles at the opposite ends of the furnace with said blower and means 115 for automatically varying the speed of said blower.

11. In combination with an open hearth furnace and a boiler adapted to be heated by waste gas from the furnace, flues connecting the opposite ends of the furnace with the boiler, nozzles arranged to discharge jets into said flues, a blower, means 120 connecting the nozzles at the opposite ends of the furnace with said blower, a motor 125

for operating said blower and means responsive to pressure variations for controlling the speed of said motor.

12. In combination with an open hearth furnace and a boiler adapted to be heated by waste gas from the furnace, flues connecting the opposite ends of the furnace with the boiler, nozzles arranged to discharge jets into said flues, a blower, means connecting the nozzles at the opposite ends of the furnace with said blower, a motor for operating said blower, a diaphragm responsive to pressure changes in said flues and in said boiler, and means operatively connected with said diaphragm for controlling the speed of said motor.

13. In combination with an open hearth furnace and a boiler adapted to be heated by waste gas from the furnace, flues connecting the opposite ends of the furnace with the boiler, nozzles arranged to dis-

charge jets into said flues, a blower, and means responsive to pressure variations between said flues and said boiler for automatically controlling the speed of said blower.

14. In combination with an open hearth furnace and a boiler adapted to be heated by waste gas from the furnace, flues connecting the opposite ends of the furnace with the boiler, nozzles arranged to discharge jets into said flues and means for alternately supplying fluid pressure to each of said nozzles, and means for automatically controlling the pressure of the fluid discharged from said jets so as to automatically compensate for slight variations in pressure between said flues.

In witness whereof, I have hereunto signed my name.

WALDEMAR DYRSSEN.
